REVERSIBLE WINDOW SASH

Gondolfo Pergolizzi and Sadie Pergolizzi,
New York, N. Y.

Application June 10, 1942, Serial No. 446,414

2 Claims. (Cl. 20—48)

This invention relates to improvements in double-hung sash windows and particularly to vertically slidable frames having glass carrying frames mounted for vertically swinging motion into the room in the slidable frame.

An object of this invention is to provide the adjoining rails of each slidable frame and its co-acting pivoted sash frame with cooperating vertical rectangular extensions facing each other and contacting in a plane and with their vertical junction extending beyond the middle of the sash frame; the rails at the opposite face contacting in a single plane and causing the said single plane face of the rails to conceal said extensions.

Another object of this invention is to provide one of said rails with a hollow circular cavity to receive the central end portion of the extension from the adjacent rail so as to permit the sash frame to swing to an obtuse angle considerably greater than ninety degrees from full open to full closed position.

Another object of this invention is to mount coil springs on the pivots of the said sash frames, the said coil springs being anchored at one end in the pivots and at the other end in a metal sleeve in the opposite rail, the said spring and pivot causing the sash frame to be automatically securely locked in either open or closed position within the range of the sash movement.

Another object of this invention is to provide a locking bolt adjacent the pivot in one of the rails and to provide two holes in the opposite rail, the holes being on opposite sides of the pivot and providing means whereby the swinging sash frame may be locked in reversed or open position, or in the normally closed predetermined position.

Another object of this invention is to provide a cut-out portion in the lower face of the window frame lower than the window sill, the said cut-out portion being of sufficient depth to permit the upper slidable frame to enter therein and causing the upper surface of the upper slidable frame to be below the lower surface of the lower slidable frame when in topmost raised position and permitting the swinging of the upper sash frame at a convenient low operating level.

Another object of this invention is to provide a ring-shaped handle on the swinging sash frame of the upper slidable frame, the handle being set in a recess in the swinging sash frame so as to be flush with the upper surface of the said swinging sash frame and to permit the upper slidable frame to be lowered without en-

countering obstruction in its movements from the lower slidable frame.

With the above and other objects in view, the invention will be hereinafter more particularly described, and the combination and arrangement of parts will be shown in the accompanying drawings and pointed out in the claims which form part of this specification.

Reference will now be had to the drawings, 10 wherein like numerals of reference designate corresponding parts throughout the several views, in which:

Figure 1 is a front elevation of a window, showing the slidable and swinging frames in 15 closed position.

Figure 2 is a cross-sectional view, the section being taken as on line 2—2 in Figure 1.

Figure 3 is a top plan view of a sash rail, on 20 an enlarged scale, and showing a pivot extending therefrom.

Figure 4 is a side view of the sash rail shown in Figure 3, on an enlarged scale.

Figure 5 is a plan view of a co-acting sash rail, on an enlarged scale, and showing a pivot 25 receiving hole.

Figure 6 is a cross-sectional view of two sash rails and a fragmentary portion of the sash frames, showing a modified pivotal mounting.

Figure 7 is a perspective view showing fragmentary portions of two co-acting rails.

Figure 8 is a perspective view showing fragmentary portions of the two co-acting rails shown in Figure 7.

Figure 9 is a cross-sectional view of two co-acting rails, the section being taken as on line 9—9, in Figure 1.

In the illustrated embodiment of the invention, the numeral 10 indicates a window frame having double hung slidable frames and comprising an upper slidable frame 11 and a lower slidable frame 12.

The slidable frames 11 and 12 have upper rails 13 and lower rails 14. Mounted in the slidable frames 11 and 12 are sash frames 15 and 16, having upper rails 17 and lower rails 18.

The sash frames 15 and 16 are mounted on pivots 19, preferably fixed in the upper rails 17 and in the lower rails 18 of the sash frames. The upper rails 13 and the lower rails 14 of the slidable frames 11 and 12 have apertures 20 designed to receive the pivots 19 in fully housed relation and for free rotation therein.

The slidable frames have vertically positioned rabbeted openings 21, 21', serving to receive vertically positioned flanges or extensions 22,

27', on the sash frames. The sash frames may thus be swung into open or closed positions with respect to the slideable frames.

In order to provide rain and snow proof junctions at the pivoted rails, I have rabbeted the rails so as to form right-angular steps in each rail. The steps interlock when the sash frames and the slideable frames are in closed position. I have thus divided the rails at substantially the middle of their horizontal depth and have formed upright walls or vertical extensions at the said middle of the rails which form a barrier to the passage of rain and snow. In order to make possible the pivotal mounting of the sash frame inside the slideable frame, I have formed each rail with a portion of the said upright wall. As shown in the drawings, the rail 13 has a vertical rectangular extension or tongue 23. The rail 17 has a vertical rectangular extension or tongue 24. The tongues are positioned on the outer face 25 of the window. The rectangular extensions 23, 24, terminate in spaced-apart planes. The adjoining faces of the rails 13 and 17, at the inner face 26 of the window 10, lie in a single plane, as best shown in Figure 1.

The extension 24 on the rail 17 stops short of the middle of the length of the sash frame and short of the pivot 19. The extension 23 on the rail 13 extends beyond the middle of the length of the sash frame, beyond the pivot 19. The line of abutment 28 of the two extensions makes an angle with the lengthwise sides of the rails. This angular relation of the extensions on the rails facilitates the relative rotation of the rails and further serves to augment the tightness of the junction of the extensions 23, 24 against the passage of rain, snow, etc. between the rails and into the room.

As best shown in Figures 3, 7 and 9, it will be noted that the rail 17 has a substantially semi-circular cavity 27, the bottom surface of which lies in the same plane 30 in the rail 17 with which the tongue 24 comes in juncture. Each cavity 27 serves to receive the central end portion 28 of the extension or tongue 23 from the adjacent or co-acting rail 13.

The structure herein described makes it possible to swing the sash frames at least one hundred and thirty-five degrees from full open to full closed position.

The said swing of the reversed sash frame enables the user to clean the window sash in the interior of the room conveniently. This swing also removes the danger of obstruction for persons moving about the room.

It is to be noted that the extensions 23, 24 occupy only approximately one-half the thickness of the rails 13 and 17, so that on the side facing the room the extensions are not visible.

As will be noted from the drawings, the extensions 23, 24 have been made of substantially rectangular form, each one occupying substantially one-half the depth of a rail. These rectangularly shaped extensions provide a sturdy structure of sufficient depth throughout the length of each extension to withstand the blows received when the window sashes are opened forcibly.

As shown in Figure 5, it will be seen that a plate 31, preferably made of metal, is secured to the rail 13. The plate 31 has an aperture in line with the aperture 26 in the rail 13. The plate 31 is preferably secured to the rail 13 by screws 32. The plate 31 has an aperture 33 to receive a vertically movable locking bolt 34, slid-

able therein. The locking bolt 34 is preferably rectangular in cross-section and is adapted to enter into either one of two rectangular apertures 35, 36 in the rail 17 for locking the swing sash in open or closed position.

When washing a sash or moving it from open or closed position it is merely necessary to raise the locking bolt and when the sash has been swung to the desired reverse position the locking bolt automatically falls into one of the apertures 35. To permit the ready entrance of the locking bolt 34 into either of the apertures 35, preferably provided by metal sleeves the entering end of the locking bolt is preferably beveled.

As shown in Figure 2, the lower end of the window 10 has a cut-out portion 37, the said cut-out portion being of sufficient depth to permit the upper slideable frame 11 to enter therein and causing the swinging sash 15 to be positioned below the lower surface of the lower slideable frame when in topmost raised position and permitting the swinging of the upper sash frame at a convenient low operating level, the same as the level of operation of the lower sash frame. This expedient of the provision of the cut-out portion 37 tends also to increase vision and at the same time saves on sash construction.

In order to swing the sash of the lower slideable frame 12 to reverse position both window frames must be in closed position. A latch on the upper rail of the lower sash is unnecessary to use when reversing and washing the window sash though it is placed in its usual position for the prevention of burglary.

Any well known standard latch which is not necessary to turn in order to release, can be additionally used on the vertical rabbeted sides of the frames. This latch serves the added purpose of preventing the window from vibrating and rattling.

It is to be noted that the contacting surfaces at the line of abutment 28 are preferably made of metal and are of sufficient depth so that the window sashes when reversed to the maximum swing, will contact each other in concealed position and prevent the window frames from being dented by being jarred against the visible outside surface of one of the rectangular extensions. It prevents hitting the side of one of the rails or the side of one of the extensions.

As best shown in Figure 3, the central end portion of the longer vertical extension, which extends beyond the pivot, rides in the cavity. The thicker or wider the frame and rails, the greater the cavity can be made and the greater the length the said central end portion can be made.

As shown in Figure 6, I have provided a modified pivotal mounting 38, comprising a pivot 39 fixed in the rail 17. The pivot 39 has an aperture 40. A coil spring 41 is mounted directly on and in contacting relation with the pivot 39 and has one of its ends 42 anchored in the aperture 40. The rail 13 has a metal sleeve 43 fixed therein and being centrally positioned with the pivot 39. The sleeve has a slot 44 in which the other end of the spring is anchored.

It is to be noted that each sash frame is mounted on two pivots. When a spring-actuated sash is swung to open position the springs will become tensioned and the locking bolt will automatically fall into one of the apertures 35 and lock the sash against swinging back to closed position by action of the tensioned springs. Upon release of the locking bolt 34 the displaced

sash will be automatically brought back to its normal closed position, when the locking bolt 34 automatically falls into the other aperture 35, and locks the sash in closed position. Under operating conditions the springs will be only slightly tensioned, so that the window sash will be slowly returned to the normal closed position.

It is to be noted that each pair of the rails 13 and 17 are interchangeable; that is, while I have shown the rails as positioned with the abutting surfaces contacting in a single plane, when facing the inside of the room, I may reverse them so that this single plane arrangement may be visible from the outside of the room. It is also to be noted that the rails of the sash and sliding frames may be reversed, so that the swinging sash rail is positioned at the upper elevation as the rail of the sliding frame.

While I have shown coil springs as the actuating means for the modified pivotal mounting, it is to be noted that this spring mechanism may be taken as representing any suitable means for performing the same function.

As shown in Figure 1, I have provided ring-shaped handles 45 on the sash frames. The handles 45 are preferably hinged at their upper ends and designed to fall into recesses (not shown). The handles are flush with the outer surfaces of the swinging sash frames to permit up and down movements without encountering any obstruction to their movements.

In accordance with the patent statutes we have described and illustrated the preferred embodiment of our invention, but it will be understood that various changes and modifications can be made therein without departing from the spirit of the invention as defined by the appended claims.

We claim:

1. In a double-hung sash window having slideable frames and coacting sash frames mounted on vertical pivots at the central portion of said slideable frames, means for preventing exposure of said pivots to snow and ice and for swinging said sash frame to an obtuse angle considerably greater than ninety degrees to bring the normally outer face of said sash frame into reverse position, said means including pivots positioned nearer one face of said window than the other face, the meeting rails of said slideable and coacting sash frames being rabbeted at substantially the mid-portion of their transverse extent or thickness to provide one vertical rectangular extension facing downwardly and a coacting vertical rectangular extension facing upwardly, said pivot being positioned in its entirety within one of said rectangular extensions all of said upwardly facing extensions and coacting downwardly facing extensions being in contacting relation all along their length, all of said upwardly facing extensions being offset vertically and laterally at a point intermediate their ends, whereby the two offset portions of each one of said upwardly facing extensions are in contacting relation at their adjacent corners, one of said extensions being longer than the other and extending lengthwise beyond the middle of said sash frame,

the contacting surfaces of said meeting rails adjoining one face of said window lying in a single plane, the contacting surfaces of said meeting rails at the opposite face of said window lying in a plane spaced apart from said first mentioned plane, said longer extensions having apertures in which said pivots are fully housed and wholly concealed, one coacting rail at the upper elevation of one of said sash frames and one rail at the lower elevation of said coacting sash frames having arcuate cavities in spaced relation from said pivots and extending close to the opposite side of said window, said cavities being sufficiently deep horizontally to permit movement therein of end portions of said longer extensions when said sash frame is swung into open position, said extensions contacting each other along a vertical plane angularly disposed relative to said rails, the outer edge of the contacting vertical surface on said shorter extension providing an abutment which limits the movement of said sash frame to open position, the distance of said abutment from said pivot being arranged to cause said sash frame to swing to open position to an obtuse angle considerably greater than ninety degrees from its closed position.

2. In a window having a sash frame mounted in a coacting frame on pivots, means for preventing exposure of said pivots to snow and ice and for swinging said sash frame to an obtuse angle considerably greater than ninety degrees to bring the normally outer face of said sash frame into reverse position, said means including pivots positioned nearer one face of said window than the other face, the meeting rails of said sash frame and coacting frame being rabbeted at substantially the mid-portion of their transverse extent or thickness to provide rectangular extensions facing each other, one of said extensions being longer than the other and extending lengthwise beyond the middle of said sash frame, the contacting surfaces of said meeting rails adjoining one face of said window lying in a single plane, the contacting surfaces of said meeting rails at the opposite face of said window lying in a plane spaced apart from said first mentioned plane, said longer extensions having apertures in which said pivots are fully housed and wholly concealed, one coacting rail having an arcuate cavity in spaced relation from said pivot and extending close to the opposite side of said window, said cavity being sufficiently deep to permit movement therein of the end portion of said longer extension when said sash frame is swung into open position, said longer and shorter extensions contacting each other along a plane angularly disposed relative to said rails, the contacting surface on said shorter extension providing an abutment which limits the movement of said sash frame to open position, the distance of said abutment from said pivot being arranged to cause said sash frame to swing to open position to an obtuse angle considerably greater than ninety degrees from its closed position.
